His Attorney.

UNITED STATES PATENT OFFICE

HARRY L. PALMER, OF SCOTIA, NEW YORK, ASSIGNOR TO GENERAL ELECTRIC COMPANY, A CORPORATION OF NEW YORK

ELECTRICAL CONTROL CIRCUITS

Application filed January 29, 1931. Serial No. 512,103.

My invention relates to electrical control circuits and particularly to automatic control circuits for electric valves.

Control circuits of the bridge type for electric valves are well known in the art. Such circuits usually comprise four impedances connected in the form of a Wheatstone bridge, at least two non-adjacent arms of which have different thermal, voltage or current resistance characteristics. Stated more broadly the non-adjacent arms have corresponding electrical properties which change relatively to each other with similar changes in their electrical or physical condition. Such an arrangement is, in effect, a reversing switch, with an off position when all four arms have equal impedances, and reversing on positions depending upon which pair of non-adjacent arms have the greater impedance. By connecting the anode circuit of an electric valve to the same source as supplies the input to the bridge, the operation of the bridge may be made to secure a reversal of polarity, or a 180 degree phase shift, in the grid potential of the valve with respect to its anode potential.

In accordance with my invention I provide a novel and simplified combination of a bridge control circuit and a hot cathode electric valve, or valves, in that at least one valve filament is connected to form one of the arms of the bridge circuit. As these valves have filaments, or heater elements, of tungsten, which has a comparatively high positive temperature coefficient of resistance, they are readily adaptable for use as the arms of bridge circuits. Such use results in a distinct saving in that the cost of at least one of the usual bridge arms is eliminated while at the same time the steady power loss in this element is saved.

An object of my invention is to provide a novel static control circuit arrangement for an electric valve or valves.

My invention will be better understood from the following description taken in connection with the accompanying drawing and its scope will be pointed out in the appended claims.

Referring now to the single figure of the

accompanying drawing, wherein I have shown diagrammatically a preferred embodiment of my invention as applied to reversing means for controlling an electric motor, such as a motor for operating an induction feeder voltage regulator, in this connection I have shown my control means connected to be responsive to the voltage of a supply circuit.

The control circuit means is indicated generally by the reference character 1, the reversing means by the reference character 2, and the reversible motor by the character 3.

The control circuit is in a form of a Wheatstone bridge having a pair of non-adjacent arms 4 and 5 composed of ordinary resistance material, such as iron, and a second pair of non-adjacent arms 6 and 7 comprising the heater elements, or filaments, 8 and 9 of a pair of electric valves. These heater elements are preferably connected to the bridge circuit by means of small filament transformers 10 and 11 as shown. The filaments, or heater elements, 8 and 9 are usually made of tungsten and consequently they have a relatively high positive temperature coefficient of resistance. The input terminals of this bridge circuit are connected across one of the phases of a three phase power supply circuit 12, while the output terminals of the bridge are connected to the primary winding of a grid transformer 13.

When the voltage of circuit 12 is normal the arms of the bridge circuit are so adjusted that the two parallel paths between its input terminals, comprising respectively resistance 4 and filament 8 on the one hand and resistance 5 and filament 9 on the other hand, are equal in magnitude so that no voltage appears across the primary winding of the grid transformer 13. If now the voltage of circuit 12 should increase the increased current flowing to the arms of the bridge will increase the resistance of the filaments 8 and 9 with the result that the bridge will be unbalanced and an alternating voltage will appear across the primary winding of transformer 13. Also, if the voltage of circuit 12 should fall the decrease in current in the bridge arms will decrease the resistance of the filaments 8 and 9 with the result that an alternating voltage of 100

opposite polarity, or a voltage shifted 180 degrees in phase will appear across the terminals of the primary winding of transformer 13. It will thus be seen that when the voltage in circuit 12 is normal no voltage is applied to transformer 13 while increases and decreases of voltage on circuit 12 cause alternating voltages of reverse polarity to be applied to this transformer.

10 The anode circuits of the valves are supplied with current from a supply transformer 14, which is also connected across one of the phases of supply circuit 12. As shown, the electrical midpoint of the secondary winding 15 of transformer 14 is connected to the filaments while the terminals of the secondary winding are connected respectively to the anodes 15 and 16 of these valves through actuating coils 17 and 18 respectively of a pair 20 of reversing relays 19 and 20. The secondary winding of grid transformer 13 has one of its terminals connected to the grids 21 and 22 of the electric valve through current limiting resistors 23 and 24, while the other terminal 25 of this secondary winding is connected to the filaments through a grid bias battery 25.

Motor 3 is connected to be energized from supply circuit 12 through the reversing contactors, or relays, 19 and 20. As shown these 30 contactors are so connected that they reverse one of the phases of the power supply circuit which is connected to this motor whenever one or the other of the relays is energized. This causes a reversal of motor 3 in 35 a manner which is well understood by those skilled in the art.

40 The electric valves may be either of the high vacuum pure electron-discharge type or the gas-filled type. I prefer, however, to use the gas-filled type because of their larger current-carrying capacity.

45 The operation of the system illustrated in the drawing is as follows: Assume that supply circuit 12 is energized and that its voltage is normal. Under these conditions the bridge circuit will be balanced, as pointed out above, no voltage will be applied to the grid transformer 13 and both electric valves will be non-conducting because their grids 50 are at the negative potential produced by the grid bias source 25.

If now the voltage of circuit 12 should decrease, an alternating voltage will be produced by the secondary winding of transformer 13, as explained above, and this voltage will be transmitted to the grids 21 and 22 of the electric valves. This voltage will be in phase with the anode potential of one of the valves and will be 180 degrees out of phase with the anode potential of the other valve because of the fact that the anode potentials of the two halves are themselves 180 degrees out of phase due to the way they are connected to the secondary winding of transformer 14. As a result the valve in

which the grid potential is in phase with its anode potential will become conducting with the result that an anode current will flow through the operating coil of one of the contactors 19 or 20. The result will be that motor 3 will be connected to circuit 12 and the motor will then start to operate. If now, the voltage of circuit 12 should rise above normal the potential of the secondary winding of grid transformer 13 will reverse with the result that the other valve will become conducting, and the valve which has been conducting will become non-conducting, thereby energizing the operating coil of the other contactor and deenergizing the operating coil of the first contactor with the result that the phase connections to motor 3 are reversed and the motor operates in a reverse direction.

70 Thus, for example, if the voltage of circuit 12 rises, the right-hand valve may, for example, be made conducting with the result that contactor 19 operates and motor 3 runs in one direction, while if the voltage in circuit 12 falls the left-hand electric valve becomes conducting and the right-hand valve becomes non-conducting with the result that contactor 20 will be energized thereby to reverse motor 3.

75 It should be understood that while I have shown my novel and simplified control scheme as applied to a pair of valves which control contactors for reversing an electric motor, my invention is not so limited and that the scheme may be used in connection with any pair of valves which are to be selectively energized.

80 While I have shown and described a preferred embodiment of my invention, it will be obvious to those skilled in the art that changes and modifications may be made without departing from my invention and I therefore, aim in the appended claims to cover all such changes and modifications as fall within the true spirit and scope of my invention.

85 What I claim as new and desire to secure by Letters Patent of the United States is,—

1. In combination, an electric valve having a plurality of electrodes and means for changing an electrical condition of one of said electrodes in accordance with changes in an electrical property of one of said electrodes.

110 2. In combination, an electric valve having a plurality of electrodes, means responsive to an electrical condition of an electric circuit for controlling an electrical condition of one of said electrodes, said means having at least two elements whose corresponding electrical properties change relatively to each other, at least one of said elements being an electrode of said valve.

115 3. In combination, a hot cathode electric valve and means for controlling the operation of said valve including a bridge circuit,

one of whose arms comprises the cathode of said valve.

4. In combination, a pair of hot filament electric valves and means for controlling 5 said valves including a voltage bridge, two of whose arms are composed of the filaments of said valves.

5. In combination, a voltage balance control device of the type having two pairs of 10 impedances having different temperature coefficients of resistance, all connected in the form of a Wheatstone bridge, a pair of hot cathode electric valves connected to be controlled by said bridge, said cathodes forming 15 one pair of impedance elements of said bridge.

6. In combination, a device for producing a control voltage to be applied to the control electrode of a three element electric 20 valve comprising a balance circuit including two impedances having different temperature coefficients of resistance, a three element electric valve, and means connecting the filament of said valve as one of the impedances of said 25 balance circuit.

7. In combination, a bridge circuit for controlling the operation of a hot cathode electric valve, a hot cathode electric valve and a filament transformer connecting the cathode of said valve into said bridge circuit as one of the arms thereof.

8. In combination, a supply circuit, a load circuit, an electric valve including a cathode having a variable coefficient of resistance for 35 controlling the energization of said load circuit, a bridge circuit including the cathode of said valve and connected to be responsive to an electrical condition of said supply circuit for controlling said valve.

40 9. In combination, an electric circuit, an electric motor, circuit controlling means connecting said motor to said circuit so as to be operable in reverse directions, hot cathode electric valves for controlling said circuit 45 controlling means, a voltage responsive bridge connected to control said valves in response to variations in the voltage of said circuit, the cathodes of said valves being connected to form two of the arms of said bridge.

50 In witness whereof I have hereunto set my hand.

HARRY L. PALMER.
